PRESSURE FLUID OPERATED TOOL

Ernest H. Shaff, Grand Haven, Mich., assignor to
 William H. Keller, Inc., Grand Haven, Mich., a
 corporation of Michigan

Application February 27, 1936, Serial No. 65,983

11 Claims. (Cl. 121—19)

This invention relates to pressure fluid operated tools and more particularly to a new and improved portable tool of the hammer type.

One object of the invention is to provide a novel tool of the above character so constructed as to prevent stalling of the impact piston.

Another object is to provide in a tool of the character indicated, a valve mechanism of novel and improved construction insuring ease in starting, and improved high-speed operation of the tool.

Another object is to provide a new and improved tool in which the recoil shocks and vibrations customarily incident to operation of the tool are cushioned and substantially prevented from transmission to the handle, thereby increasing the efficiency of the tool, decreasing the breakage hazard and rendering the tool safer and less fatiguing in use.

In the attainment of these objects the tool embodies a valve mechanism in which a disk valve of substantially wafer thinness and having an extremely short range of movement is adapted to control effectually the flow of pressure fluid to opposite ends of the piston chamber so as to effect rapid reciprocal movement of the impact piston, and means coating with the valve maintains a permanently unbalanced pressure condition on one side of the valve to eliminate entirely any possibility of the tool stalling due to equalization of pressure. Furthermore the tool embodies a new and improved cushioning construction utilizing in combination the shock absorbing qualities of mechanical means and compressible pressure fluid.

Another object resides in the improvements in construction and the novel relationships of parts by which the foregoing and other objects and advantages of the invention may be carried into practice simply and economically.

Other objects and advantages will become apparent from the following description taken in connection with the accompanying drawings, in which:

Figure 1 is a longitudinal sectional view through a tool embodying the principles of the invention, the valve being shown in the position it occupies during the forward stroke of the piston.

Fig. 2 is a fragmental sectional view of the rear end of the tool taken on a similar plane as Fig. 1 but showing the valve in the position it assumes during the rearward movement of the piston and also showing the parts of the tool in the relative positions they occupy when the cushioning means is in full operation.

Fig. 3 is a perspective assembly view of the valve mechanism showing the face of the rear valve-casing member.

Fig. 4 is a sectional plan view taken substantially on the plane of line 4—4 of Fig. 1.

Fig. 5 is a sectional plan view taken substantially along the plane of line 5—5 of Fig. 1.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The tool shown in the present instance is of the type generally referred to as a "chipping-hammer" which comprises an elongated barrel 10 having a chamber 12 for a piston 13. An impact tool 14 is carried by the forward end of the barrel; and at the rear end of the barrel is a valve mechanism, indicated generally by the numeral 15. Pressure fluid may be supplied in the usual manner through a valve controlled passage 17 in a handle portion 18 and serves to reciprocate the piston which during its reciprocatory movement controls the exhaust of pressure fluid from the piston chamber.

While in the preferred construction, the valve mechanism 15 embodies substantial improvements, it may be of generally similar form and operation as set forth in the E. H. Shaff Patent No. 1,924,812 issued August 29, 1933. Accordingly it comprises a cylindrical casing made from two coaxially aligned members in the form of circular plates 19 and 20 held in a predetermined fixed relation by dowel pins 21 which fit in complementary holes 22 in the plates (see Fig. 3). The opposed faces of said plates are recessed to provide therebetween a valve chamber 23 having forward and rear faces 24 and 25, respectively, and said faces are spaced apart a distance only slightly greater than the thickness of a substantially wafer-thin, reciprocable disk valve 26 which is enclosed therein.

The assembled valve casing is preferably of greater diameter than the piston chamber 12 and is supported in closing relation to the rear end 50 of the latter. For this purpose, the rear end of the barrel 10 has an enlarged portion or head 27 projecting beyond the piston chamber and having a bore 28 of a diameter to receive the valve casing 15. The latter is held against a shoulder 29 55

at the forward end of the bore 23 by suitable means such as a ring nut 38 threaded into the rear end of the bore and coating with the rear face of the casing plate 19. To hold the casing 5 against turning, the forward ends of the dowel pins 21 engage with holes 22^a (see Fig. 3) in the shoulder 28. In its rear face, the ring nut is provided with wrench sockets 31.

For delivering pressure fluid from the passage 10 17 in the handle to the valve chamber 23, a pressure fluid port 32 opens from the passage 17 toward the rear face of the casing plate 19, and the latter is equipped with a plurality of supply ports 33 disposed adjacent the periphery of the valve 15 chamber.

The forward face of the valve chamber has a plurality of shallow circular recesses 34 coaxial with the supply ports 33. By alining the axes of these ports and recesses substantially with the 20 peripheral surface of the disk valve 26, pressure fluid may be admitted to the valve chamber upon either side of the valve, depending on the position of the latter with regard to the respective faces of the valve chamber.

25 When the disk valve 26 is in its rearward position, shown in Fig. 1, the pressure fluid will pass to the forward side of the valve chamber for delivery to the rear end of the piston chamber 12 by means of a plurality of inlet ports 35 (herein 30 seven in number) provided in the forward valve plate 20.

In order to provide maximum operating efficiency by affording the greatest practicable inlet area for the pressure fluid and without weakening 35 the structure of the member 20, the invention contemplates an improved arrangement of the inlet ports 35. I have found that this end may be attained very desirably by locating one port in the center of the casing member 20 and grouping 40 the remaining ports around the center port. Each inlet port, moreover, may be spaced substantially the same distance from every adjacent inlet port. As shown, there may be seven of the 45 inlet ports 35, all equally spaced apart and their combined inlet area permitting free and efficient passage of pressure fluid into the rear end of the piston chamber 12. This arrangement of the inlet ports also permits reduction to a minimum of the necessary movement of the disk valve 26 50 away from the forward face of the valve chamber to admit the requisite volume of pressure fluid to the piston chamber.

For the purpose of permitting movement of the disk valve 26 away from the forward face 55 of the valve chamber with utmost rapidity and with the least frictional or vacuum drag, contact between the valve and the face should be exceedingly limited. Practically this end may be attained by the provision of very narrow annular 60 flanges or rims 37 individually surrounding the inlet ports 35. These rims serve to maintain the valve disk spaced from the major area of the forward face 24 when the valve disk is in sealing relation to the ports. The internal diameter of 65 each of the rims may be slightly greater than that of the ports so as to eliminate resistance to the passage of pressure fluid thereinto, the action being similar to that obtained by beveling the ports. Also, the edges of the rims should be 70 carefully machined so as to lie in a uniform plane for engagement simultaneously in complete sealing relation when the disk valve moves thereagainst during operation of the tool. Through this construction, the sensitivity of the 75 valve is greatly increased because a continuous

air cushion is maintained over the major area of the forward chamber face 24, thus facilitating unsealing movement of the valve.

Pressure fluid for returning the piston 13 toward the rear of the barrel after impact with 5 the tool 14, is delivered in the usual manner to the forward end of the piston chamber 12 through delivery ports 38 which communicate with a plurality of elongated passages 39 in the wall of the barrel. At their rear ends the passages 39 10 open into the valve mechanism 15 through angular passages 40 which are formed in the casing members 19 and 28 and which open into the rear side of the valve chamber 23 through inlet ports 42 in the rear wall of the chamber, two 15 such inlet ports being provided in the present instance.

Where the rear valve chamber face 25 concentrically surrounds the ports 42 it is quite smooth to coat sealingly with the rear face of the valve 20 disk 26, but the total area of contact between the valve and the face 25 is preferably limited by the provision of large shallow recesses 43 in the face intermediate the ports 42. When the valve is moved into sealing relation to the ports 25 42, small quantities of air are apparently trapped in such recesses 43. In any event it has been found that this construction insures instantaneous movement of the valve to unsealing position, thus counteracting any tendency of the valve 30 to cling to said face.

Reciprocation of the piston 13 is effected in the manner described in the aforesaid Shaff Patent No. 1,924,812, pressure fluid being admitted by the disk valve 26 alternately to the rear or the front of the piston chamber through the inlet ports 35 or 42, respectively. The valve 26 is movable for this purpose under the control of the piston in response to pressure variations or inequalities developed in the piston chamber on the opposite sides of the piston. In its cycle of movement, the piston alternately opens or closes forward or rear exhaust ports 44 and 45, respectively, which are suitably spaced longitudinally of the piston chamber as is customary. Exhausted pressure fluid is passed to atmosphere through longitudinal exhaust passages 47 in the wall of the barrel communicating with the exhaust ports 44 and 45 and with outlet ports 48 which open into a muffler 49.

It has been found, however, that in the prior construction when the pressure fluid is admitted to the tool under reduced pressure, as where the operator wishes to start a cutting operation slowly and carefully, the tool frequently stalls. This results when the piston is moving slowly and reaches substantially the mid-position in its reciprocal cycle wherein it is in closing relation to both the forward exhaust ports 44 and the rearward exhaust ports 45. At this time, apparently, the pressure in both the forward and rear parts of the piston chamber becomes substantially equal, and the piston lacks sufficient momentum to carry it beyond one set of exhaust ports. When this state of pressure equalization arises, the disk valve is held inoperative by the balance of pressures developed within the valve chamber 21.

The present invention, therefore, contemplates a construction in which the valve is biased or unbalanced for movement in one direction upon an equalization of pressures on opposite sides of the piston. Herein, this end is attained by providing means such as a small axial unbalancing piston 59 which is secured fixedly to the valve 75

disk in any suitable manner that will not distort the thin metal thereof. Desirably, the valve may be axially apertured as at 52 and the piston may have a reduced portion 53 which in assembly fits within the aperture and is suitably secured permanently in place.

To receive the unbalancing piston 50, one face of the valve chamber, herein the rear face, has a bore 54 within which the unbalancing piston fits 0 in fairly snug but freely slidable relation. Communicating with the rear end of the bore 54 is a passage 55 which opens to atmosphere by communicating through the valve casing members 19 and 20 with one of the exhaust passages 47. 15 It will be apparent, therefore, that a small though vital area of the valve 26 will remain free of pressure under all conditions during operation, thereby effectually preventing equalization of pressure on its opposite sides even though the 20 pressure within the piston chamber 12 on opposite sides of the piston approaches a state of equalization. Thus, the tool will not stall because the valve, due to its unbalance, will move rearwardly and restore normal operation of the 25 tool.

The invention also contemplates the provision of means for cushioning the handle 18 of the tool against vibrations and recoil shocks developed by the rapidly reciprocating piston 13. Accordingly, the handle carries a sleeve 57 which is closed at its rear end by a part of the handle and which opens forwardly for slidably receiving the head 27 of the barrel. Coacting means on the parts 30 permit relative reciprocal movement of the 35 head and sleeve but substantially prevent relative rotary movement thereof. Conveniently, such means may take the form of one or more bosses 58 integral with the rear edge of the head, and in assembly fitting within complementary bores 40 59 in the handle portion at the rear of the sleeve (Figs. 1 and 2).

Transmission of vibrations from the barrel to the handle is prevented by a combination of mechanical and pressure fluid cushions, one of 45 these cushions being disposed to absorb those vibrations which act forwardly upon the tool and another cushion being disposed to absorb the vibrations acting rearwardly on the tool. By way of example, the mechanical cushion may be arranged to absorb the forwardly acting vibrations. 50 For this purpose the sleeve 57 may extend substantially beyond the forward end of the head 27 of the barrel so that suitable resilient means such as a coil spring 60 may be inserted between the forwardly extending part of the sleeve and the body of the barrel 10 and with its rear end 55 in engagement with the front end of the head. The spring may be maintained under predetermined tension by suitable retaining means such as a flanged nut 62 threaded into the forward end of the sleeve and having a shouldered recess 63 for receiving the forward end of the spring. Through this arrangement the head 27 is normally maintained in a fixed position with respect 60 to the handle, that is, the rear end of the head may normally abut part of the sleeve-enclosing portion of the handle, but vibrations acting forwardly on the tool will be absorbed by the spring.

The rearwardly acting vibrations may be absorbed effectually by one or more pressure fluid cushions which may be developed between the rear end of the head 27 and the handle in the 70 operation of the tool. Desirably, this may be accomplished by providing the rear closure of the sleeve 57 with a forwardly projecting plunger,

herein comprising an axial boss 64 which is adapted to fit within the bore of the ring nut 30 and which closely approaches the rear face of the valve casing member 19 in the inoperative condition of the tool. The pressure fluid port 32 5 may pass through the boss 64 and the forward mouth of the port may open in substantial radially spaced relation to the supply ports 33 in the rear face of the casing member 19. When live pressure fluid is delivered through the port 10 32 to the forward end of the bore, substantial force will be exerted by the fluid against the rear of the valve casing, such force being substantially augmented by the restriction upon passage of the pressure fluid to the supply ports 33 15 due to the close proximity of the forward end of the boss 64 to the rear of the valve casing. Preferably the spring 60 is tensioned to yield a certain amount under the force exerted by the live pressure fluid, thereby allowing the barrel 20 to move forwardly in the sleeve 57 and permitting the development of a live pressure fluid cushion which will absorb vibrations acting rearwardly on the barrel.

Preferably the live fluid pressure cushion is 25 confined in its action to a limited area of the coacting parts of the device and may be supplemented by an incidental or auxiliary fluid cushion active between the major area between the rear end of the barrel and the handle of the tool. 30 This end may be attained by forming the boss 64 throughout its principal extent of substantially smaller diameter than the internal diameter of the ring nut 30 and interposing a closely fitting 35 packing 65 between the boss and the inner wall of the nut. Preferably, the packing 65 may be formed of leather or other suitable material and is of substantially apertured cup-shape with the principal portion of its exterior surface in contact with the wall of the bore of the ring nut 40 and its inner edge clamped in fixed position adjacent the base of the boss 64 by suitable means such as a nut 67 threaded upon the boss. The forward edge of the packing may be beveled outwardly as at 68 so that live pressure fluid 45 acting thereon will force the same more closely into sealing relation. Through this construction the live pressure fluid cushion will be confined to an area of the same diameter as the bore of the ring nut 50 30.

Contemporaneously with development of the live pressure cushion, the major area of the opposed portions of the rear part of the barrel and the handle are separated, providing an auxiliary cushion chamber 69 (Fig. 2). A slight vacuum 55 condition is developed in the cushion chamber 69 at the beginning of operation and has a braking or retarding effect on the separating movement of the parts, thereby preventing initial recoil when pressure fluid is first admitted to the tool. 60 After the spring 60 has reached a predetermined compression due to the relative forward movement of the barrel, it will counteract and balance the force of the live pressure fluid thus maintaining the head 27 of the barrel resiliently 65 suspended. As this suspended condition is attained, the auxiliary cushion chamber may be vented to atmosphere through a relief vent 70 which passes radially through the sleeve 57. Live pressure fluid that may escape into the auxiliary 70 cushion chamber will thus be vented and prevented from developing pressure which would tend to separate the parts further.

As soon as the supply of live pressure fluid is interrupted, the spring 60 acts to return the 75

barrel to its original position. A substantial volume of air will, however, be trapped in the auxiliary cushion chamber 69 and will dissipate slowly, thus causing the barrel to return rearwardly gradually and without recoil or clashing of parts.

From the foregoing it will be clear that the present invention affords a new and improved pressure fluid actuated tool of sturdy and durable 10 construction and which may be constructed very economically of few and relatively simple parts that have been designed and correlated to coact with utmost efficiency to attain exceptionally high speed, smooth and uniform operation. The 15 tool is capable of higher operating speeds than prior devices due to the increased sensitivity of the fluid controlling disk valve and its exceptionally short range of movement. Under no 20 circumstances can the tool stall from equalized internal pressure during any phase of operation, because the permanent unbalancing means coacting with the fluid controlling valve effectually prevents fluid pressure balance in the valve mechanism. Of great advantage, moreover, is 25 the novel combination of coacting mechanical and fluid cushions embodied in the tool whereby breakage of parts due to operating vibrations is practically eliminated; and the absorption of such vibrations prevents their transmission to 30 the handle of the tool and permits the operator to attain greater accuracy and make a cleaner cut without the physical detriments resulting from recoil and vibration usually attendant upon the use of most prior tools of this character.

35 I claim as my invention:

1. A pressure fluid operated tool having, in combination, a barrel including a piston chamber with a piston reciprocable therein, the forward end of said barrel being arranged to receive a tool 40 to be impacted by said piston and the rear end of said barrel having means including a valve casing coacting therewith and embodying valve mechanism for controlling the movements of the piston, means securing said valve casing in said 45 barrel and having a bore opening rearwardly to expose the rear part of said valve casing, an internally cylindrical member closed at its rear end and movably surrounding the rear end of said barrel, said member having a boss fitting reciprocally in said bore, means normally acting in the inoperative condition of the tool to move said boss toward said rear part of said valve casing, means for delivering pressure fluid to the forward 50 end of said boss, fluid supply ports in said rear part of said valve casing substantially restricted from receiving pressure fluid due to the normal disposition of said boss relative to said valve casing, and packing means surrounding said boss and coacting with the wall defining said bore, 55 said packing means being arranged for substantially preventing escape of pressure fluid rearwardly from said bore so as to develop a pressure area at the end of said boss to move the latter in opposition to said normally acting means partially out of said bore and relatively move said 60 barrel and member incident to the delivery of pressure fluid of predetermined force.

2. A pressure fluid operated tool having, in combination, a piston chamber with a piston reciprocable therein, and means for controlling the movements of the piston comprising a valve casing at the rear end of the piston chamber and a valve member in the form of a thin disk of substantial diameter, said casing providing a 65 valve chamber for the valve member having for-

ward and rear faces spaced apart a distance only slightly greater than the thickness of said valve member, means for supplying pressure fluid to said valve chamber on either side of said valve member comprising a supply port adjacent the periphery of said valve chamber, delivery passages communicating at their forward ends with the forward part of said piston chamber and having their rear ends in communication with said valve chamber through said rear face thereof, and means concentric with the latter ends of said passages and coactive with said valve member for effecting a sealing relation against the entrance of pressure fluid into said passages in one position of said valve, said rear face of said valve chamber having inwardly offset portions of substantial area which remain out of contact with said valve member to provide fluid cushions therebetween when the valve is in sealing relation to said passages, whereby to facilitate rapid movement of said valve member away from said sealing relation.

3. In a pressure operated tool of the character described, the combination of a barrel having a longitudinal piston chamber and a piston reciprocable therein, said barrel having a bore of larger diameter than said chamber coaxial therewith and opening rearwardly, a valve casing seated in the inner end of said bore in closing relation to said chamber and having its outer face substantially inwardly of the outer end of the bore, said outer face of said casing being apertured to receive pressure fluid, a ring nut threaded into said bore for holding said valve casing in place and having a smooth axial bore dimensioned to expose the apertured portion of said outer face of the casing, a handle member movably associated with the rear end of the barrel including a fixed forwardly projecting plunger arranged to project movably into said ring nut bore and having a pressure fluid passage communicating with said apertured portion of the casing, and means providing a seal to prevent escape of pressure fluid rearwardly out of said ring nut bore.

4. A pressure fluid operated tool having, in combination, a barrel cylindrically chambered to provide a piston chamber, a piston reciprocable therein, a handle portion including a sleeve member surrounding a rear portion of said barrel and having an enclosing surface opposing the rear portion of the barrel, an auxiliary plunger projecting forwardly from said surface and having a pressure fluid supply port opening through the forward end thereof, said rear portion of said barrel having an enlarged bore communicating with said piston chamber, means for controlling the movements of the piston comprising a valve casing thinner than the depth of said bore seated therein and in closing relation over the rear end of said piston chamber, and means having a central opening secured in said bore for maintaining said valve casing fixedly in operative position and coacting with said rear end of said barrel to provide with said enclosing surface of said sleeve member a chamber enabling relative reciprocal movement between the sleeve member and the barrel, said plunger extending into said central opening to deliver pressure fluid to said valve controlling means.

5. In a pressure fluid operated tool, in combination, a barrel including a piston chamber and a piston reciprocable therein, said barrel being arranged forwardly to receive a tool to be impacted by said piston and having a rearwardly

opening recess, valve means for controlling operation of said piston including a housing within said recess having a ported rear face offset inwardly relative to the rear end of the barrel, 5 means enclosing said rear end of the barrel, and means for delivering pressure fluid to said valve means for operating said piston including an axially movable plunger projecting into said recess and having a pressure fluid delivery port 10 communicating with the space between the forward end of the plunger and said rear face of said housing means, the ported area of said rear face being so related to said plunger that the passage of pressure fluid to the valve means is 15 controlled proportionately to the size of said space as governed by the distance of the forward end of the plunger from said rear face.

6. In a pressure fluid operated tool, in combination, a barrel including a piston chamber 20 and a piston reciprocable therein, said barrel being arranged at its forward end to receive a tool to be impacted by said piston, means assembled with the rear part of said barrel providing a valve chamber housing having a rear face formed with supply ports opening therethrough, a sleeve closed at its rear end and slidably surrounding the rear end portion of said barrel, yieldable means operative normally to maintain the barrel rearwardly in said sleeve, 25 and means for delivering pressure fluid including a port opening forwardly in spaced relation to said supply ports through a part of the closed end of the sleeve which opposes said rear face, the space between said rear face and the opposing surface of said part affording only restricted communication for the passage of pressure fluid between said ports in the initial operation of the tool and being arranged to permit an increased rate of flow incident to forward movement of 30 said barrel resulting from the development of pressure in said space in opposition to said yieldable means during continued operations of the tool.

7. In a pressure fluid operated chipping hammer, a barrel having a reciprocal piston therein, handle means mounted upon the rear end of said barrel for axial movement relative thereto and including a passage for a controllable supply of motive fluid, resilient means normally operative 45 to force said barrel and said handle means together and tensioned to yield responsive to predetermined force acting to separate said barrel and handle means axially, valve means for controlling the supply of motive fluid to said barrel, and a pair of juxtaposed separable surfaces respectively rigid with said handle means and said barrel and arranged to receive the motive fluid therebetween with a pressure equal to said predetermined force and effect the axial separation 50 of said barrel and handle means, said surfaces controlling the flow of motive fluid from said passage to said valve means as an incident to the separating movement thereof, as a result of which said piston may be actuated progressively 55 from slow to rapid reciprocation where the character of the chipping operation requires a cautious start, and as the pressure of the fluid forces separation of said surfaces a shock absorbing pressure fluid cushion will be developed therebetween to cooperate with said resilient means in relieving the tool of vibration.

8. In combination in a fluid actuated percussion tool of the character described, a barrel adapted to carry a chipping tool at one end and 60 having a reciprocable piston therein to impact

the tool, a handle member coacting with the rear portion of said barrel for relative axial movement and having means for delivering a controllable supply of motive fluid, a pair of opposed pressure separable surfaces rigid with said handle member and said barrel respectively for receiving the motive fluid therebetween and controlling the passage thereof to said barrel, resilient means of predetermined tension acting to hold said barrel and said handle member in the relative 10 position wherein said surfaces are close together, said resilient means being yieldable responsive to the development between said surfaces of fluid pressures sufficient to overcome said tension and permit separation of said surfaces so as to form 15 a live pressure fluid cushion to resist operating vibration of said barrel rearwardly, means carried by said barrel for controlling operation of said piston including a chambered casing for receiving the controlled supply of pressure fluid 20 from between said surfaces, said casing having a pressure sensitive valve member therein to govern the passage of the motive fluid therethrough responsive to pressure differential arising in the reciprocations of said piston, and 25 means for preventing a balanced pressure condition within said casing and barrel which would tend to stall the piston when running slowly at the beginning of a chipping operation.

9. A pressure fluid operated percussion tool 30 comprising, in combination, a barrel having a reciprocal piston therein, handle means mounted upon the rear end of said barrel for relative axial movement and including a passage for a controllable supply of pressure fluid, resilient means 35 normally operative to force said barrel and said handle means together and tensioned to yield responsive to predetermined force acting to separate said barrel and said handle means axially, valve means for controlling the supply of motive 40 fluid to said barrel, a pair of juxtaposed separable surfaces respectively rigid with said handle means and said barrel and arranged to receive the pressure fluid therebetween with a pressure 45 equal to said predetermined force to effect the axial separation of said barrel and handle means, said surfaces by their spacing controlling the flow of pressure fluid from said passage to said valve means so that as the pressure increases whereby to move said surfaces apart in opposition to said resilient means the speed and force of the piston will be increased proportionately, and means for retarding the separating movement of said surfaces to insure a smooth and progressive acceleration of the piston from starting 50 to full speed even though the pressure fluid is initially admitted under full pressure through said passage into the space between said surfaces.

10. A pressure fluid operated percussion tool 60 of the character described comprising, in combination, a barrel for housing the operating mechanism of the tool, a handle member having a sleeve portion slidably embracing one end of said barrel and a closure portion opposing said end, 65 said barrel and handle member being separable to a limited extent by relative axial movement, means on the inner side of said closure portion and said barrel end to provide two substantially separated chambers when said inner side of said 70 closure portion and said barrel end are separated to said limited extent, resilient means normally operative to force said handle member and said barrel together whereby the spaces of said chambers will be practically eliminated, said closure 75

- portion having a pressure fluid supply passage opening into one of said chambers so that upon the development of sufficient live pressure in said one chamber said barrel and said handle member will be forced apart in opposition to said resilient means while the other chamber will develop a vacuum condition therein to retard the separating action, and a vent for said vacuum chamber adapted to be opened only after separation to said limited extent has been effected by the pressure fluid in said one chamber.
11. A pressure fluid operated tool having, in combination, a piston chamber with a piston reciprocable therein, and means for controlling the movements of the piston comprising a valve casing at the rear end of the piston chamber having therein a valve member in the form of a thin disk of substantial diameter, said casing providing a valve chamber for the valve member having forward and rear faces spaced apart a distance only slightly greater than the thickness of said valve member, means for supplying pressure fluid to said valve chamber on both sides of said valve member and including a supply port adjacent the periphery of said valve chamber, a delivery pas-

sage communicating at the forward end thereof with the forward part of said piston chamber and having the rear end thereof in communication with said valve chamber through said rear face thereof, a portion of said rear face surrounding the latter end of said passage and coactive with said valve member for effecting a sealing relation against the entrance of pressure fluid into said passage in one position of said valve, a substantial area of said rear face of said valve chamber being recessed to remain out of contact with said valve member to provide a fluid cushion when the valve member is in sealing relation to said passage, and a plurality of ports communicating through said forward face with the rear end of said piston chamber individually circumscribed by separate raised rims for substantially line contact fluid-sealing relation with said valve member, the area of said forward face surrounding said rims being in constant communication with said supply port to expose the face of the valve member to live pressure fluid tending to assist in shifting the valve member from fluid sealing relation with said rims.

ERNEST H. SHAFT. 25
